UNITED STATES PATENT OFFICE.

GEORGE L. DUTCHER, OF DOUGLAS, AND CHARLES W. BOYLE, OF BRADLEY,
ASSIGNORS, BY DIRECT AND MESNE ASSIGNMENTS, TO CHARLES H. ADAMS
AND EDWARD T. VAN OSTRAND, BOTH OF ALLEGAN, MICHIGAN.

FEED-REGULATOR.

SPECIFICATION forming part of Letters Patent No. 449,580, dated March 31, 1891.

Application filed January 9, 1890. Serial No. 336,340. (No model.)

To all whom it may concern:

Be it known that we, GEORGE L. DUTCHER, of Douglas, in the county of Allegan and State of Michigan, and CHARLES WILLARD BOYLE, of Bradley, in the county of Allegan and State of Michigan, have invented a new and Improved Feed-Regulator, of which the following is a full, clear, and exact description.

This invention relates to feed-delivery devices of the class employed in connection with roller-mills and purifiers, the object of the invention being to provide for the even delivery of the stock to the shaker and to provide for the regulation of the amount of stock delivered from the shaker to the rollers.

To the ends above named the invention consists of certain novel constructions, arrangements, and combinations of elements, which will be hereinafter fully described, and specifically pointed out in the claims.

Reference is to be had to the accompanying drawings, forming a part of this specification, in which similar figures and letters of reference indicate corresponding parts in all the views.

Figure 1 is a longitudinal sectional view of our improved rock-shaker and feed-regulator for roller-mills and purifiers. Fig. 2 is a cross-sectional view on line 2 2 of Fig. 1. Fig. 3 is a view on line 3 3 of Fig. 1, and Fig. 4 is a detail view illustrating the arrangement of the driving-shaft.

In the drawings, 10 represents an inclosing case, in which there are arranged one or more hoppers, as A A', said hoppers being arranged to deliver stock to trays 11, that are mounted upon links 12. The stock is delivered to the hoppers through openings a, formed in the top of the case 10, passing downward through said openings upon spreading-blocks 13, that are triangular in cross-section, such blocks acting to throw the stock laterally upon the trays and upon deflecting-plates 14, that are arranged as shown best in Fig. 2, the stock passing downward from the deflecting blocks or plates to the trays. Beneath the trays there is arranged a rock-shaft 15, which has an upwardly-extending crank 16, that fits in an aperture b, formed in a downwardly-extending flange 17, that is carried by the trays.

To the outer end of the shaft 15 there is secured a lever-arm 18, having a number of apertures, as indicated by dotted lines in Figs. 1 and 2, such apertures being provided to receive a coupling-pin or set-screw 19, which passes through apertures formed in a socket 20, carried by a connecting-rod 21, this arrangement being adopted to provide for the regulation of the stroke. To the other end of the rod 21 there is secured an eccentric-strap 22, that runs upon an eccentric 23, carried by a driving-shaft 24, which said shaft is provided with a pulley 25, arranged to receive a driving-belt.

From the construction above described it will be seen that if the shaft 24 be rotated the shaft 15 will be rocked and a reciprocating motion will be imparted to the trays, thus distributing the stock evenly thereon.

In order that the amount of stock fed from the trays may be regulated, I provide plates 30, that are adjustably connected to arms 31, the connection between the plates and arms being established by means of bolts 32 and nuts 33, the lower ends of the arms being slotted, as shown at c, to provide for the passage of the bolts. A further adjustment is secured through the medium of rock-shafts 35, upon which the arms 31 are mounted, the arrangement being such that by turning the shaft through the medium of its lever arm or handle 36 the arms, and with them the plate 30, may be raised or lowered.

Any suitable means may be provided for holding the handles 36 and rock-shafts 35 in any adjusted position. In the present instance we have shown set-nuts 36^x.

A still further adjustment of the plates is secured by providing each plate with an arm 40, upon which there is adjustably mounted a weight 41, the weight tending to counteract the effect of the pressure of the stock upon the inner face of the plate.

From the construction above described it will be seen that the stock may be delivered to the trays so that it will rest very evenly thereon, that the shaking of the trays may be regulated to suit the requirements of the stock that is being operated upon, and that the amount of stock fed from the trays may

be regulated to a nicely through the me-
dium of the plates 30.

Strips 50 are arranged in connection with
the trays 11, as shown in Fig. 1, such strips
5 serving to prevent the material from banking
against the plates 30.

Having thus described our invention, we
claim as new and desire to secure by Letters
Patent—

- 10 1. In a feed-regulator for roller mills, and
in combination with a suitable hopper and
inclosing casing, shaking-trays 11, provided
with strips 50, arranged underneath said hop-
per, a means of shaking the trays, plates 30,
15 arranged near the free end of the trays pro-
vided with adjustable weights 41, arranged
as described, arms 31, secured to said plates,
rock-shafts 35, journaled in said casing and
provided with handles 36, arranged outside
20 of said casing, and means for securing the
said handles and rock-shafts in any adjusted
position, substantially as described, and for
the purposes herein set forth.
2. In a feed-regulator for roller-mills, and
25 in combination with a suitable hopper and
casing-blocks 13, arranged in the hopper, shak-
ing-trays 11, provided with strips 50, arranged
underneath said hopper, a means of shaking
the trays, plates 30, provided with arms 31,

and rock-shafts 35, journaled in the casing, 30
adjustable connections between the arms and
plates, arms that extend outward from the
plates, and weights carried by the levers
adapted to move toward and away from the
plates, substantially as set forth.

3. In feed-regulators for roller-mills, and
in combination with a double hopper and a
suitable inclosing casing, blocks 13, arranged
within the hoppers, trays 11, provided with
strips 50, arranged beneath the hoppers, a 40
flange 17, secured to the under side of the
trays, rock-shafts arranged underneath the
trays, having a crank 16, engaging said flange,
a lever 18, carried by rock-shafts provided
with a number of apertures adapted to re-
ceive a coupling-pin 19, a connecting-rod 21,
provided with a socket 20, having corre-
sponding sockets adapted to pin 19 for the
regulation of the stroke, an eccentric-strap
22, secured to rod 21, an eccentric 23, and 45
driving-shaft 24, arranged substantially as
and for the purposes set forth.

GEORGE L. DUTCHER.
